UNITED STATES PATENT OFFICE

CHARLES T. JACOBS, OF NEW PROVIDENCE TOWNSHIP, UNION COUNTY, NEW JERSEY,
ASSIGNOR TO MIESSNER INVENTIONS, INC., A CORPORATION OF NEW JERSEY

METHOD AND APPARATUS FOR THE PRODUCTION OF MUSIC

Application filed September 22, 1931, Serial No. 564,305. Renewed November 17, 1932.

This invention relates to musical instruments and systems and more specifically to those in which the vibrations of tuned vibrators are translated into electric oscillations and such oscillations employed for the actuation of further apparatus. Vibrators as contemplated in the invention are those whose vibration contains not only a fundamental frequency component but also one or more coincident higher frequency components harmonically related to the fundamental. The fundamental and these higher frequency components may each be termed a partial of the composite vibration. Typical of such vibrators are, of course, strings under longitudinal tension; and strings are shown as the vibrators in the accompanying drawings. I do not wish to limit my invention to use with strings, however, it being adaptable for use with any other such tuned vibrator as above mentioned.

In the U. S. Patent 1,906,607, issued to me May 2, 1933, I pointed out that the oscillations produced by translation of the vibrations of the various points on a vibrating string were of different waveform; but that while an infinite number of such waveforms were available by such translation at different points, they did not represent as large as possible a variety of tone qualities. I showed, however, that if oscillations produced by translation of the vibrations of two or more string points were combined, new tone qualities became available; and further, that if the several oscillations were controllable before combination in respect of relative amplitudes and relative phases, an extremely wide variation in final waveform and harmonic structure, and hence tone quality, could be effected. Methods and apparatus were disclosed in that application for such multi-point translation, relative amplitude and phase control, and subsequent combination of oscillations. The present application is concerned principally with extensions and modifications of the means and methods therein disclosed, together with specific means and methods for producing more particular types of output tones.

Thus it is an object of my invention to pro-

vide improved means and methods for translating the vibrations of tuned vibrators into electric oscillations of a harmonic structure selectable within wide limits; and likewise for selectively varying over a wide range the harmonic structure or waveform of electric oscillations produced by translation of the vibrations of tuned vibrators. 55

A further object is the provision in a musical instrument of the class described of improved vibration-oscillation translating means and methods suitable for producing almost any desired quality of tone; and likewise such means and methods for producing a quality of tone selectively variable over a 60 wide range. 65

It is another object of my invention to provide improved and convenient controls for effecting the variation and selection abovementioned; and more specific objects 70 are the provision of means and methods for obtaining from the vibrations of tuned vibrators electric oscillations of various particular harmonic structures: e. g., containing only or predominately even or odd numbered 75 partial components, containing substantially pure fundamental, or containing other more or less particular groups of partials. Other and allied objects will more fully appear from the following description and the 80 appended claims. 85

In the detailed description of my invention, hereinafter set forth, reference is had to the accompanying drawings, of which:—

Figure 1 is a cross-sectional view of a 85 string and its supports, together with mechano-electrical translating systems and electrical and electro-acoustic apparatus embodying my invention;

Figure 2 is a partial plan view of the 90 mechanical apparatus shown in Figure 1;

Figure 3 is a view similar to Figure 2 but illustrating an alternative plan arrangement of the mechanical apparatus shown in Figure 1; and 95

Figure 4 is a further cross-sectional view of a string and its supports illustrating a particular arrangement of translating devices adapted to the production of practically pure fundamental frequency oscillations 100

from string vibrations having appreciable upper partial components.

Thus in Figure 1, I show a string 1, strung for example between tuning pin 2 in wrest plank 3 and hitch pin 5, over triangular bar 4, under "capo" or pressure bar 6, and over rear triangular bar 7, capo 6 and triangular bar 7 limiting or defining the active vibratory length of the string. A hammer 8, actuated for example by the well understood piano key and action, not shown, may be provided underneath string 1 for vibrating the latter, but it will be understood that any means or device for producing either sustained or decadent vibration of the string at its fundamental and at least one harmonic frequency may be substituted for hammer 8. A plan view of this apparatus showing a group of strings 1 of progressive lengths for vibration at progressive frequencies of the musical scale appears as Figure 2.

Below the several strings 1 will be seen, in both Figures 1 and 2, conductive strips 9, 10 and 11, preferably of small cross-section, and above the several strings similar conductive strips 12 and 13. These strips may conveniently be supported by somewhat flexible insulating strips 14, to which the conductive strips may be cemented, as is more fully disclosed in the co-pending application of Benjamin F. Miessner and myself, Serial No. 558,207, filed August 20, 1931. The conductive strips will each be seen to be slightly spaced from each of the strings 1; and such spacing is in general preferably as small as possible without producing any contact between the strips and any string 1 under conditions of maximum vibration of the latter. It will be appreciated, of course, that such spacing of a conductive strip will in general be greater, the nearer such strip to the center of the strings. While particular means of securing the insulating strips 14 have been disclosed in the joint co-pending application above-mentioned, it is sufficient for the purposes of this specification that they be secured in any convenient manner preserving the insulation afforded by them to the several conductive strips 9, 10, 11, 12 and 13 after fixed thereto.

The conductive strips may be electrically connected, through various switching arrangements comprising group of switches 15, group 16, and double pole double throw switch 17, hereinafter more fully discussed, to the grids of a plurality of vacuum tubes shown in Figure 1 as 21, 22 and 23. The cathodes or filaments of the tubes may be connected together and energized as by battery 24. A tap 25 on battery or other potential source 26 may provide a source of anode current for the tubes. Between the cathodes of the tubes and the negative of battery 26 may be provided a condensively by-passed resistor 27 for the biasing of the grid of each

tube, through an associated high resistance 28, negatively with respect to its cathode. In the output circuit of each tube may be connected the primary of a transformer, such transformers being designated as 31, 32 and 33, respectively, in Figure 1.

Across the secondaries of transformers 31, 32 and 33, respectively, may be provided tapped resistors 41, 42 and 43; and the taps and extremities of each resistor may be connected to a bank of single-pole, single-throw switches, such banks of switches being shown as 51, 52 and 53 respectively. The central switch in each bank may be connected to the electrical center of the associated tapped resistor, such switch in each bank being designated as 54. The electrical centers of the tapped resistors, and the common connection of each switch-bank, may be connected together as shown and to the potentiometer 29; and the variable contact of this potentiometer may be connected to the grid of a fourth vacuum tube 34. The cathode or filament of this tube may conveniently be paralleled with those of tubes 21, 22 and 23; and its anode current may be supplied from the tap 25 on battery 26. In the output circuit of this tube may be connected amplifier 35; and to the amplifier may be connected loud-speaker 36. Electrostatic shielding 37 may be disposed about the tubes 21, 22, 23 and 34 and their associated circuits, about the leads thereto from the conductive strips 9, 10, 11, 12 and 13, and around such strips. Such shielding may be connected to the positive terminal of battery or potential source 26 and also to capo 6 or to some other member or members electrically connected to strings 1, whereby the latter may be rendered at the potential of such positive terminal of battery or source 26. It will be understood, of course, that tubes with unipotential cathodes suitably energized from alternating current may be substituted for tubes 21, 22, 23 and 34 and battery 24; likewise that a suitable rectifying, filtering and voltage dividing system may replace battery or source 26, etc.

Consideration being given to the manner of functioning of the apparatus shown in Figure 1, it will be seen that between each strip 9, 10, 11, 12 and 13 and each string 1 a small electrostatic capacity exists; and that, with the switches in groups 15 and 16 open and switch 17 in the left-hand position as shown, the total capacity formed between each one of the strips 9, 10, and 11 is in series with one of the resistors 28 and the battery 26. These capacities are therefore charged to the potential of battery 26. Upon vibration of any string 1 in a vertical plane, as produced by impact therewith of hammer 8, the capacity between strip 9 and the region of such string immediately thereabove will vary oscillatorily, as will likewise but in less degree the total capacity between strip 9 and

the strings. This oscillatory capacity variation, because of the fixed charge in the capacity, produces an oscillatory variation of the voltage across the capacity. The frequency, waveform and harmonic structure of this voltage variation correspond respectively to the like characteristics of the vibration of the mean point of the vibrated string opposite strip 9; and such oscillatory voltage variation, or A. C. voltage, is applied to the grid of tube 21. Similarly an A. C. voltage corresponding in its characteristics to the vibration of the mean point of the vibrated string above strip 10 appears at the grid of tube 22; and a voltage corresponding to the vibration of the mean string point above strip 11 at the grid of tube 23. These voltages, in amplified form, respectively appear across the tapped resistors 41, 42 and 43, as will be understood.

If now there be closed one switch of each bank, other for example than switch 54, there will be seen to be provided a continuous circuit including a portion of each of the tapped resistors 41, 42 and 43, and including the potentiometer 29. Thus voltages appearing across the three tapped resistors may be made to appear in combination across potentiometer 29; and it will be seen that the absolute (and hence the relative) amplitudes, of these several voltages may be regulated, and that the absolute (and hence relative) phases thereof may be reversed at will, by choice of the switch closed in each bank. Elimination from potentiometer 29 of voltage derived from any one or more of the tapped resistors may be effected by closing the switch 54 in the associated switch bank, whether or not other switches in that bank be closed; or by closing two or more switches connected to taps on opposite sides of the electrical center of the resistance. Furthermore certain amplitudes of voltage not available upon closing of any one switch in a bank may be obtained by closing two or more switches connected to taps on the same side of the electrical center of the associated resistance, since part of the resistance is thereby short-circuited, the load on the associated tube and transformer altered, and the voltage across the residual resistance thereby varied. Each individual switch in the switch-banks may conveniently be controlled by a "tablet" such as is customarily employed for the "stop" regulation in the conventional pipe organ, such tablet requiring to have merely the usual two positions, one maintaining the associated switch open and the other maintaining it closed.

The composite voltage made to appear across potentiometer 29 may be thereby regulated in amplitude; and may thereafter be amplified by tube 34 and amplifier 35 and translated into sound by loudspeaker 36.

The choice of position of the various conductive strips associated with the various strings determines to a large extent the types and range of tone qualities available from the system. In general, as might be expected from the segmental nature of the vibration of a string at its various harmonically related partial frequencies, the nearer the center of the string a translating device be placed, the more predominate will be the lower partial components in the oscillations thereby produced, relative to the higher partial components therein. It is, of course, an inherent advantage of the basic system disclosed that oscillations generated by two or more translating devices variously placed along a string may be so combined in respect of amplitude and phase that their fundamental frequencies, and frequently also other of their lower partial frequencies, are entirely or largely mutually cancelled out, producing resultant oscillations relatively much richer in higher partials. It is obvious, however, only on certain adjustments of the combining means—e. g., the switch-banks 51, 52 and 53—that such cancellation can be effected; and in order that the fullest advantage be derived from the wide range of combining adjustments available in a given case, it is desirable that the oscillations produced by the combining adjustment which most accentuates the lower partials, be sufficiently rich in higher partials to make them ordinarily musically useful. Then the adjustments which most effectively cancel out the lower partials need not be invariably employed, instead being available for the production when desired of harmonic structures especially rich in higher partials. To this end I have in general found it desirable to employ translating devices relatively near the extremities of the strings. Thus strips 9, 10 and 11 in Figures 1 and 2 are respectively shown at approximately 1/20, 1/12 and 1/8 of the length of each string forward from the rear end of the active vibratory portion thereof.

It is possible, however, to obtain a harmonic structure very rich in higher partials without positioning of translating device or system extremely near the extremities of the strings, and without special adjustments of the combining controls. This may be accomplished by employing two translating devices or systems permanently or optionally connected together independently of the combining controls, and so arranged that the lower partial components produced by each oppose each other. Thus in Figures 1 and 2 I show conductive strip 12 positioned at approximately 1/6 of the length of each string forward from the rear end of the active portion thereof, and group of switches 15, by one of which it may optionally be con-

nected in parallel with strip 11, which as above-mentioned is positioned at approximately 1/8 string length forward from the rear ends. It is important, with a capacitive translating device and for the purpose at present under discussion, that strip 12 be on the opposite side of the string from strip 11—otherwise the lower partial components would re-enforce instead of opposing each other. Of course if certain magnetic forms of translating devices be substituted for the capacitive system shown, control over phase may be effected without positioning on opposite sides of the string, as will be understood. When strip 12 is parallel with strip 11, the combination yields oscillations equivalent, in relative weakness of the lower partials, to those produced by a single strip much nearer the end of the string than either of them. A special arrangement of translating devices very useful for the production of colorful tonal effects, for frequency doubling or for the more or less complete elimination of even partials from oscillations and output tones, is the use of translating devices at least approximately similarly spaced from the two ends of the active vibratory portion of each string—i. e., symmetrical longitudinally about the center of the string. Thus in Figures 1 and 2 I show conductive strip 13 positioned at approximately 1/20 of string length back of the forward ends of the several strings 1, a similar spacing to that of strip 9 from the rear ends. By setting the switch 17 in the right-hand position instead of the left-hand position as shown, it will be seen that strip 13 is substituted for strip 11, making active the three strips 9, 10 and 13. If now switch 54 of bank 52 be closed, so that strip 10 is inactive in contributing to the final oscillations, there remain active the symmetrically placed strips 9 and 13. If the separate outputs from each of these two strips be adjusted to introduce into the circuit of potentiometer 29 similar amplitudes and aiding phase of the fundamental component, by closing of appropriate switches in banks 51 and 53, the combined oscillations will be without even partials. If the similarity of amplitudes of the separate oscillations be somewhat upset, the combined oscillations will have some even, but will predominate in odd, partials. If similarity of amplitude but opposition of fundamental phase be established by the switch-banks 51 and 53, the combined oscillations will be without the original fundamental frequency or other odd partials, thus producing the octave of the string frequency. If the fundamental phase opposition be maintained but amplitude similarity somewhat upset, the combined oscillations will contain some odd, but will predominate in even, partials. Again, small or large amplitudes of oscillations in either phase from strip 10 may be combined with

the various combinations from strips 9 and 13; or with oscillations from strip 13 alone, in which latter case the resulting oscillations will be characterized by incomplete tendencies toward even or odd partial predominance, the two strips 10 and 13 being in a most general sense but by no means exactly, symmetrically placed about the center of the string.

As long as strip 13 is to be used alone to supply oscillations to tube 23 and switch-bank 53, it is of no significance whether it be placed above or below the strings 1. But in order that it may on occasion be combined in parallel with other strips by group of switches 16, and to the end that it may then serve in general to emphasize even partials rather than odd, it has been shown on the opposite side of the strings from the strips 9, 10 and 11. It may be noted that a strong tendency toward even partial predominance may at times give the musical effect of coincident playing of higher octaves of the notes actually played.

Switches such as groups 15 and 16, which parallel an additional strip selectively with other strips already in circuit, and such as 17, which selectively connects the input of one of the separate amplifying tubes to one of two or more strips, are very useful adjuncts to the oscillation-combining controls, permitting a much wider range of harmonic structure choice than would otherwise be possible without considerably more complex apparatus. Thus, while more than three separate input tubes and switch-banks may be employed, the use of switches performing such functions as 15, 16 and/or 17 makes possible almost as wide harmonic structure control without such additional apparatus. The number of separate input tubes may even be reduced to two without tremendous sacrifices of the flexibility of the system if suitable switches such as 15, 16 and 17 be employed. Switches in the groups 15 and 16 and double pole double throw switch 17, being each a two position switch, may conveniently be controlled by "tablets" as above-mentioned for the switches in the banks 51, 52 and 53.

For purposes of simulation of the tone quality of particular instruments, or for any of several possible reasons dictating a particular choice of tonal characteristics, a departure may at times be desirable from the effects produced by the sole action of any one of the translating systems (e. g., strips 9, 10, 11 etc.) or by the joint action of any two or more in any particular combination effected as by the switch-banks. Thus, for example, a particular translating system, or combination of such systems with particular amplitude and phase adjustments of the output oscillations therefrom before combination, may for a particular purpose prove sat-

isfactory in the middle musical register, but at the same time may provide oscillations in the bass register which contain too high relative amplitudes of lower partials. As a means of correcting this and similar difficulties, I show in the output circuit of tube 34 a tone control device 45, which may for example comprise an inductance 46, a capacity 47, and a resistance or potentiometer 48. With the elements of the device arranged as shown, either the inductance or the capacity may be made effective to shunt the output of tube 34, by adjustment of the variable contact of the potentiometer toward that element. The potentiometer is preferably of four times, or more than four times, the lowest value of resistance which may be shunted across the output of this tube with negligible effect on efficiency. This permits a setting of the movable contact, i. e., at mid-position electrically on the resistance of the potentiometer, such that negligible effect, when desired, is felt from the inclusion of the device in circuit. The choice of inductance and capacity values may readily be determined with the aid of principles well understood in the art of audio-frequency amplification, regard being had for particular results desired in a given case.

It will be understood, of course, that the more effective be the inductance as a shunt across the line, the greater will be the attenuation of lower partials of the bass tones produced by the system. On the other hand, the more effective be the capacity as a shunt, the greater will be the attenuation of the higher frequencies, particularly of the higher partials of the high treble tones. It will further be understood that the tone control device shown illustrative only, any of several well-known circuits and/or devices directed to similar ends being capable of substitution therefor.

Such tone control devices may further be employed, and I hereinafter claim as my invention their employment, to control one or more of the separate series of oscillations before combination thereof by the combining apparatus. Thus I have shown a similar tone control device 45' in the output of each of the three tubes 21, 22 and 23. In this position they may be made to produce a wide variety of effects; including that of an accentuation of either very low or very high frequencies, which is accomplished by attenuating that range of frequencies in one of two sets of oscillations derived from two translating devices or systems and being principally opposed against each other, at least as to their components in that range, by the phase adjustment effected by the switch-banks or equivalent combining system.

When each translating system, e. g., strip 9, 10, 11, etc., is positioned opposite a corresponding fractional position of each string,

the whole system tends to be uniform in action with respect to the translation of particular partials of the vibration of each string. This condition may not always be desirable; and as a method of providing departure from such uniformity of particular partial translation characteristics in a rational manner, I have included illustrative Figure 3. Here the fractional distance of each strip 9, 10, 11, 12 and 13 from the respectively nearer end of the string will be seen to be progressively less, the longer the string; but the ratios between themselves of the spacings of the several strips from such ends of each string have been maintained constant—e. g., strip 10 is $5/3$ as far from the rear end of each string as strip 9, strip 11 is $5/2$ as far as strip 9, strip 13 the same distance from the front end of each string as strip 9 is from the rear, etc. This particular arrangement tends to decrease the strength of the lower partials, relative to that of higher partials, progressively as string length increases. It will be understood that this is illustrative only, a wide variety of methods of departure from the similarity of respective spacings shown in Figure 2 being available to produce these discriminating effects.

Occasionally it may be desired to produce for some musical purpose a practically pure tone; or, again, practically pure tones may be desired at some point in a musical instrument in which a desired harmonic structure is built up by synthetizing a group of harmonically related such tones. To obtain such a tone from a string or other mechanical vibrator vibrating with a complement of partial frequencies, I show in Figure 4 a special arrangement of translating devices. Thus three conductive strips 18, 19 and 20 may be provided, positioned at $1/4$, $1/2$ and $3/4$ of active string length respectively from the front end of the active portion of the string. These three strips may be electrically connected together and to the input of an electrical system similar to that shown in Figure 1—e. g., to the grid to tube 21 in that figure. strips 18 and 20 must be similarly spaced from string 1, thus producing oscillations having a similar amplitude of fundamental component; and the spacing of strip 19 from string 1 may be adjusted until the amplitude of fundamental component produced by it is twice that produced by each of the other two devices. Under these conditions no 3rd, 5th, 11th, or 13th, partials will be present in the output oscillations; which condition will be found convenient as a test for proper position of strip 19. Due to the symmetry of strips 18 and 20 about the longitudinal center of the string, and to their aiding connection, they jointly translate no even partials; strip 19 being at the center of the string, where no even partial vibration takes place, consequently translates none; and the

3rd, 5th, 11th and 13th partial are eliminated as abovementioned.

Consequently of the partial's up to and including the 14th, only the 7th and 9th are translated; and if string vibration at these partial frequencies be kept low by the exciting means, as by hammer 8 striking string 1 at approximately 1/8 its active length back of the front end thereof, as is well understood 10 in the piano art, the net upper partial content of the translated oscillations will be very low. Furthermore for at least a limited range of simultaneously available musical notes, these upper partials may be reduced to 15 a negligible value by means of the tone control device 45 in the output of tube 21 and/or of tube 24. Tubes 22 and 23 and associated apparatus need not, of course, be employed in this embodiment of my invention.

20 It will be understood that while I have shown and described an electrostatic form of translating device or system, the principles of my invention are equally applicable to any other form of translating device or system 25 which may be associated with, and be actuated by the vibration of, particular portions of the vibrators. It will further be understood that while I have shown tapped resistors 41, 42 and 43, and banks of switches 51, 30 52 and 53, for controlling the amplitudes and phases of the separate series of oscillations before combinations, other forms of amplitude and phase controls such for example as tapped resistors and multipoint single-pole 35 switches, or center-tapped potentiometers, may be substituted therefor, or the variable controls entirely omitted when selective particular partial translation is not required, and the other features of my invention at 40 the same time retained. It will finally be understood that the apparatus and circuits shown are capable of wide modification without departure in the combinations, or methods of use, thereof from the spirit or 45 scope of my invention, as hereinabove disclosed and in the appended claims defined.

I claim:—

1. In a musical instrument, the combination of a plurality of tuned vibrators; means 50 for vibrating said vibrators; a plurality of mechanico-electric translating systems, each system being associated with a portion of each vibrator different from that with which each said other system is associated and 55 being arranged to translate into a series of electric oscillations the vibrations of the therewith associated such portions; adjustable means individually operative on at least one of said series of oscillations for altering the relative amplitudes of components thereof on an absolute frequency basis; and means 60 following said adjustable means for combining the oscillations of the several such series.

2. In a musical instrument, the combina-

tion of a plurality of tuned vibrators; means for vibrating said vibrators; a plurality of mechanico-electric translating systems, each system being associated with a portion of each vibrator different from that with which each said other system is associated and being arranged to translate into a series of electric oscillations the vibrations of the therewith associated such portions; selective means for varying the characteristics of the oscillations of the several such series relative to each other; adjustable means individually operative on at least one of said series of oscillations for altering the relative amplitudes of components thereof on an absolute frequency basis; and means following said selective and adjustable means for combining the oscillations of the several such series.

3. In a musical instrument, the combination of a plurality of tuned vibrators; means for vibrating each of said vibrators; a plurality of systems each for translating into a series of electric oscillations the vibration of a different portion of each of said vibrators; a plurality of electric work circuits; means for applying the oscillations of each of such series across a respective such work circuit to develop a voltage therein; a plurality of taps on each said work circuit; and an electrical circuit, including a plurality of two-position switches individually connected to said taps, wherein voltages from said work circuits may be variously combined.

4. In a musical instrument, the combination of a tuned string; means for vibrating said string; two mechanico-electric translating devices positioned on opposite sides of said string, respectively adjacent portions thereof having a slight longitudinal separation, each for translating the vibration of the adjacent said portion into a series of electric oscillations; and means for combining said two series of oscillations.

5. In a musical instrument, the combination of a tuned string; means for vibrating said string; two mechanico-electric translating devices, respectively adjacent two points on said string which divide the active length thereof into three parts of which the outside two are substantially equal, each of said systems being arranged to translate into a series of electric oscillations the vibration of the adjacent said point; and means for combining said two series of oscillations.

6. In a musical instrument, the combination of a tuned string; means for vibrating said string; two mechanico-electric translating devices, respectively adjacent two points on said string which divide the active length thereof into three parts of which the outside two are substantially equal, each of said systems being arranged to translate into a se-

ries of electric oscillations the vibration of the adjacent said point; selective means for reversing the phase of one of said series of oscillations; and means following such selective means for combining the oscillations of said two series.

7. The combination of a string; means for vibrating said string; a mechanico-electric translating device adjacent a point of said string distant by one-quarter of its active length from one end thereof and a mechanico-electric translating device similarly adjacent a point of said string distant by three-quarters of its active length from said end thereof, 10 each of said translating devices being arranged to translate into a series of electric oscillations the vibration of the adjacent said point; a mechanico-electric translating device adjacent the central point of the active 15 length of said string and arranged to translate the vibration of said central point into a series of electric oscillations having a fundamental frequency component substantially double that of each of said two first mentioned series; and means for combining said 20 three series of oscillations additively with respect to their fundamental frequency components.

8. The combination of a string; means for 25 vibrating said string; a mechanico-electric translating device adjacent a point on said string distant by one-quarter of its active length from one end thereof and a mechanico-electric translating device similarly adjacent 30 a point of said string distant by three-quarters of its active length from said end thereof, each of said translating devices being arranged to translate into a series of electric oscillations the vibration of the adjacent said 35 point; a mechanico-electric translating device positioned opposite the central point of the active length of said string and arranged to translate the vibration of said central point into a series of electric oscillations having 40 a fundamental frequency component substantially double that of each of said two first-mentioned series; means for combining said three series of oscillations additively with respect to their fundamental frequency 45 components; and means for attenuating residual upper partial components from said combined oscillations.

9. In a musical instrument, the combination 50 of a plurality of strings tuned to progressive fundamental frequencies; means for vibrating said strings; a mechanico-electric translating system associated with, and arranged to translate into a series of electric oscillations the vibration of, a point on each 55 string, the distances of said points from the ends of the respective strings having a progressive relation to the respective lengths of said strings; at least one other mechanico-electric translating system, each said other 60 system being adjacent, and arranged to trans-

late into a series of electric oscillations the vibration of, another point on each string, the distances of said last named points from the ends of the respective strings being a substantially constant multiple of the respective 70 said first-mentioned distances; and means for combining said series of oscillations.

10. In a musical instrument, the combination 75 of a plurality of tuned, electrically conductive vibrators; a plurality of electrically conductive members, each said member being positioned adjacent a portion of each of said vibrators different from that to which each other said member is adjacent and forming electrical capacities with said portions; an electrical work circuit unilaterally connected to said vibrators; a source of D. C. potential included in said work circuit; and means for connecting said conductive members selectively to said work circuit.

11. In a musical instrument, the combination 80 of a plurality of tuned vibrators; means for vibrating said vibrators; a plurality of electrical work circuits; a number greater than said plurality of mechanico-electric translating systems, each system being associated with a portion of each of said vibrators different from that with which each said other system is associated and being arranged 85 to translate into a series of electric oscillations the vibrations of the therewith associated said portions; and means interposed between said translating devices and said work circuits, and selective with respect both to said translating systems and to said work circuits, for applying to said work circuits said various series of oscillations.

12. The method of producing electric oscillations from a tuned vibrator and of regulating their harmonic structure, which consists in vibrating said vibrator at a plurality of its partial frequencies, in translating the vibrations of each of a plurality of portions of said vibrator into a series of electric oscillations, in attenuating components of the oscillations of one of said series in a degree varying with absolute frequency, and in thereafter combining the oscillations of the several such series.

13. The method of producing electric oscillations from a tuned vibrator and of regulating their harmonic structure, which consists in vibrating said vibrator at a plurality of its partial frequencies, in translating the vibrations of each of a plurality of different portions of said vibrator into a series of electric oscillations, in regulating the characteristics of the oscillations of the several such series relative to each other, in attenuating components of the oscillations of one of said series in a degree varying with absolute frequency, and in thereafter combining the oscillations of the several such series.

14. The method of producing electric oscillations in which alternately numbered par-

- 5 tials predominate from a tuned string, which consists in vibrating said string at a plurality of its partial frequencies, in translating into a series of electric oscillations the vibration of each of two portions of said string substantially symmetrically located longitudinally about the center of the active length of said string, and in combining the oscillations of the two such series.
- 10 15. The method of producing electric oscillations from a tuned string and of varying their harmonic structure, which consists in vibrating said string at a plurality of its partial frequencies, in translating into a series of electric oscillations the vibration of each of two portions of said string substantially symmetrically located longitudinally about the center of the active length of said string, in regulating the characteristics of the two such series relative to each other, and in thereafter combining the oscillations of the two such series.
- 15 20 16. The method of generating electric oscillations of substantially pure fundamental frequency from a tuned string vibrating at its fundamental and other of its partial frequencies, which consists in translating into a series of electric oscillations the vibration of a point on said string distant by one quarter of the active length of said string from one end thereof, in translating into a series of electric oscillations of similar fundamental component amplitude the vibration of a point on said string distant by three
- 35

quarters of the active length of said string from said end thereof, in translating into a series of electric oscillations having a fundamental component twice that of each of said two first-mentioned series the vibration of the central point of the active length of said string, and in combining said series of oscillations additively with respect to their fundamental components.

17. The method of generating electric oscillations of substantially pure fundamental frequency from a tuned string vibrating at its fundamental and other of its partial frequencies, which consists in translating into a series of electric oscillations the vibration of a point on said string distant by one quarter of the active length of said string from one end thereof, in translating into a series of electric oscillations of similar fundamental component amplitude the vibration of a point on said string distant by three quarters of the active length of said string from said end thereof, in translating into a series of electric oscillations having a fundamental component twice that of each of said two first-mentioned series the vibration of the central point of the active length of said string, in combining said series of oscillations additively with respect to their fundamental components, and in attenuating residual upper partial components of said combined oscillations.
